(57) **CLAIM**

The ornamental design for a fuel container as shown and described.

DESCRIPTION

FIG. 1 is a top front perspective view of a fuel container, showing our new design;

FIG. 2 is a top rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a side elevation view thereof; and,

FIG. 8 is an opposite side elevation view thereof.

The broken lines shown are included for the purpose of illustrating portions of the fuel container that form no part of the claim.
